UNITED STATES PATENT OFFICE.

JOHN PARKIN, JR., OF SAN RAFAEL, CALIFORNIA.

RHEOSTAT.

1,424,515.

Specification of Letters Patent. Patented Aug. 1, 1922.

Application filed April 25, 1921. Serial No. 464,142.

To all whom it may concern:

Be it known that I, JOHN PARKIN, Jr., a citizen of the United States, and a resident of San Rafael, Marin County, State of California, have invented a new and useful Rheostat, of which the following is a specification.

My invention relates to devices for varying the resistance in an electric circuit, and one of the objects of the invention is to provide a variable resistance device comprising few parts of very simple construction, and having a graduated dial to permit close adjustment of the resistance. Another object is the provision of a variable resistance device of the dial type, practically all of which lies in front of the panel on which it is mounted, leaving the rear of the panel free. Another object is the provision of a dial type rheostat which is very easy to install.

My invention possesses other objects and features of advantage, some of which, with the foregoing, will be set forth in the following description of my invention. It is to be understood that I do not limit myself to the showing made by the said description, as I may adopt variant forms of my invention within the scope of the claims.

In the drawings, Fig. 1 is a side elevation, largely in section, of one of my rheostats mounted on a panel. Fig. 2 is a rear view of the graduated disk or dial. Fig. 3 is a front elevation of my rheostat.

My rheostat comprises a knob 2 of bakelite or other non-conducting material molded about the core or center 3, preferably of brass, and threaded to receive the screw 4, which acts as the shaft upon which the device is mounted. The periphery of the knob is knurled to permit of its digital control. At the base of the knob and concentric therewith is the graduated disk or dial 5, also preferably of bakelite, fixed for rotation with the knob and shaft 4 by the nut 6 threaded on the shaft.

A flanged bushing 7 is fixed in the panel 8 and held therein by the nut 9 threaded on the bushing at the rear of the panel. The shaft 4 comprises a screw, the head of which engages the rear end of the bushing. The parts are assembled in the relation shown in Fig. 1 and the screw shaft 4 turned in firmly. The nut 6 is then turned sufficiently to free

itself from the bushing 7 and still tighter to bind the graduated disk to the knob. The disk 5 is beveled on its periphery, the beveled edge being provided with graduations 11 so that the amount of resistance in the circuit may be visually evaluated. An index point 12 is fixed in the panel for ready reading of the dial.

The rear or under surface of the dial near its periphery is provided with a groove 13 in which a helical coil of resistance wire is disposed. The groove extends into the body of the disk and inwardly toward its center of rotation so that the resilience in the coil of resistance wire will tend to retain the coil in the groove. One end 14 of the wire of the coil is hooked through an aperture through the flange 16 which forms the inner boundary of the groove 13 and the other end 17 of the resistance coil is carried toward the center of the disk and caught under the nut 6, with which it forms an electrical contact. Therefore the resistance coil is electrically connected to the conductor 18 forming one side of the circuit in which the rheostat is used, and connected to the nut 9.

Fixed to the panel 8 by bolts 19 is a spring contact arm 21 arranged to resiliently engage the coils of the resistance element as shown in Fig. 1. A conductor 22, forming the other side of the circuit in which the rheostat is used is electrically connected to one of the bolts 19. Formed on the under surface of the flange 16, either by a pin set in the material of the flange or by an integral extension of the flange is a stop 23 adapted to engage the contact arm 21 to prevent further rotation of the dial when the index 12 is in registration with the zero reading on the dial.

From the above it will be clear that in the position of parts shown in Fig. 3 the contact arm 21 is out of engagement with the resistance element and the circuit through the rheostat is therefore broken. By turning the dial to the right the circuit is closed and a decreasing amount of the resistance wire is thrown into the circuit until the minimum is reached upon a full revolution of the knob.

I claim:

1. A variable resistance device comprising a rotatably mounted graduated disk, a variable resistance element circularly dis-

posed about said disk and fixed for rotation therewith, and a knob for the digital control of said disk.

2. A variable resistance device comprising a rotatably mounted graduated disk, a variable resistance element circularly disposed about said disk and fixed for rotation therewith, and a knob for the digital control of said disk fixed thereon.

10 3. A variable resistance device comprising a rotatably mounted knob, a graduated disk fixed concentrically on said knob, a variable resistance element circularly disposed about said disk and fixed for rotation therewith, a conductor on said disk for connecting said element to one side of a circuit, and a conductor slidably engaging said element for connecting it with the other side of said circuit.

20 4. A variable resistance device comprising a rotatably mounted knob, a graduated disk having an annular groove therein and fixed concentrically on said knob, a variable resistance element disposed in said groove, a conductor on said disk for connecting said element to one side of a circuit, and a conductor slidably engaging said element for connecting it with the other side of said circuit.

30 5. A variable resistance device comprising a rotatably mounted shaft of conducting material, a knob of non-conducting material fixed on said shaft, a graduated dial fixed at the base of said knob for rotation therewith, a helical coil of resistance

wire circularly disposed about said knob and having one of its ends connected to said shaft, a conductor adjacent said knob and slidably engaging said coil, and a conductor slidably engaging said shaft.

40 6. A variable resistance device comprising a panel of non-conducting material, a shaft of conducting material rotatably mounted in said panel, a graduated disk having an annular groove therein fixed on said shaft, a variable resistance element disposed in said groove and connected at one end with said shaft, a digitally controlled knob fixed on said disk, an arm of conducting material fixed on said panel and resiliently engaging 45 said element, a plate of conducting material on the rear of said panel electrically connected to said shaft, and a spring interposed between said shaft and said plate.

50 7. A variable resistance device comprising a rotatably mounted graduated disk having an annular groove in the under side thereof, a variable resistance element disposed in said groove, and a knob fixed on said disk for its digital control.

55 8. A variable resistance device comprising a rotatably mounted graduated disk having an inwardly sloping annular groove in the under side thereof, a resilient variable resistance element disposed in said groove, 60 and a knob fixed on said disk for its digital control.

In testimony whereof, I have hereunto set my hand.

JOHN PARKIN, JR.
